UNITED STATES PATENT OFFICE.

HERBERT C. PAWSON, OF TORONTO, ONTARIO, CANADA, ASSIGNOR OF ONE-HALF TO
ELIAS E. SLAGHT AND SAMUEL L. SQUIRE, BOTH OF TORONTO, CANADA.

BOILER IMPROVER AND FUEL ECONOMIZER.

Application filed August 4, 1925. Serial No. 48,136.

This invention relates to boiler improvers and fuel economizers for heating air and admitting it to the interior of a boiler or furnace for facilitating combustion within the furnace combustion chamber. Heretofore these devices have been mounted intermediate the ends of furnace flue pipes which made it necessary to remove the device when the pipe was pulled down to clean it, which is objectionable as most of these devices require to be set in operation by a skillful operator. Another objectionable feature resulting from the above arrangement is that the heated air must pass through the products of combustion in the pipe to get to the combustion chamber. My object is to provide a simple device of the above character which will overcome the above objectionable features and which may be cheaply manufactured and readily mounted in position on the furnace.

I attain my objects by forming my boiler improver and fuel economizer as an extension of the pipe collar of the furnace where-by the furnace pipe may be taken down without disturbing the economizer, and by extending the inner end of the economizer into the furnace and providing it with a laterally directed opening for directing the air around the interior of the furnace combustion chamber and out of the path of the products of combustion passing through the collar. The constructions are hereinafter more fully described and illustrated in the accompanying drawings in which

Fig. 1 is a section of part of the upper end of a furnace showing my device in position thereon; and

Fig. 2 is a side elevation of my device showing the damper partly opened.

In the drawings like numerals of reference indicate corresponding parts in the different figures.

1 is the upper end of the combustion chamber of the furnace which is provided with the usual pipe collar 2. The fuel economizer comprises an annular one piece chamber 3, a damper 4 and an air inlet pipe 5. The inner end 3^a of the outer wall of the chamber is adapted to be received in the collar 2 and the outer end 3^b of this wall is substantially the same diameter as the

outside diameter of the collar. This permits the same flue pipe 6 which originally fitted on the collar to be fitted on the chamber. The device is secured to the collar by means of set screws 7 threaded in a ring 3^c which is formed integral with and spaced from the end 3^a to form an annular groove for receiving the collar 2. Air is admitted to the outer end of the chamber by a pipe 8. The inner end of the chamber extends below the inner end of the collar, and a laterally directed opening 3^e, or openings, is formed in its outer wall communicating with the interior of the combustion chamber close to its wall. Above its lower end a partition 3^d is formed in which are formed the air openings 3^e. The number and size of these openings determines the flow of air to the openings 3^e.

By arranging the latter to direct the air laterally into the combustion chamber, the air is directly brought into the combustion chamber without being interfered with by the flow of products of combustion passing through the central opening of the chamber 3 and the flue pipe 6. Its passage by gravity of the combustion chamber of the furnace is by this arrangement much facilitated. This also tends to prevent the air outlet opening 3^e from being clogged by soot. The end of the pipe 8 communicating with the atmosphere is positioned below the outlet opening 3^e to tend to prevent flue gases being forced out through the device when a damper 9 is closed.

The damper is slightly less in diameter than the diameter of the central passage of the chamber so that the latter is not entirely closed off when the damper is in its closed position. A lever 10 pivoted on lugs 11, formed integrally with the chamber 3, carries the damper. One end of this lever is adapted to rest on the top of the chamber to support the damper in its closed position. The other end of the lever is serrated to engage a pivoted arm 12 which is so weighted or shaped that it tends to fall away from the chamber and passes over the serrations on the lever when the latter is rocked to open the damper. Immediately the lever is released the arm engages a tooth to hold the damper as adjusted. The free end of the

lever is passed out through a slot 18 in the flue pipe 6 and is provided with a suitable hand grip.

The above arrangement of pivoting the damper permits it, if closed, to be blown open if a gas explosion occurs in the furnace and if the damper is partly open, when an explosion occurs, the above described releasable locking means will permit the damper to be blown fully open. Danger of gas escaping into the building is thus prevented.

In practice the size and number of the openings 3^e in the partition 3^d are determined by the grate area of the boiler on which the device is to be installed. Having settled the total area desirable, the workman drills up through the bottom of the annular chamber and through the partition, afterwards plugging the holes in the bottom.

I find with my device that the efficiency of the heating system is much increased relative to the amount of fuel burned, so much so that in some cases where the efficiency of the system has not been up to the required rating, by the use of my device it is possible to so increase the efficiency as to render the installation of a larger boiler unnecessary. The heat is held more steady and uniform, better combustion of the fuel is obtained leaving only a fine ash, and greater time may be taken between firing periods.

The device, it will be noted, is very compact and simple to manufacture and install.

35 What I claim is:—

1. A boiler improver and fuel economizer including an annular chamber having integral inner and outer walls; a ring formed integral with and spaced from the outer wall 40 to form an annular groove adapted to receive a pipe collar of a furnace; the outer end of the outer wall being substantially the same diameter as the diameter of the said collar, the inner end of the chamber 45 being adapted to extend below the inner end of the collar and having a laterally directed opening formed therein; an inlet pipe communicating with the end of the chamber remote from the opening; and a partition 50 formed integral with the inner and outer walls of the chamber above the opening, the

partition being provided with openings adapted to regulate the flow of air to the laterally directed opening.

2. A boiler improver and fuel economizer 55 including an annular chamber having one end of its outer wall adapted to be received in a pipe collar of a furnace and to extend below the collar into the interior of the furnace, the other end being adapted to receive a flue pipe, an air opening being formed at the upper end of the chamber and a laterally directed opening at the lower end of the chamber, through which the air from the chamber may pass close to the inside of the casing of the furnace; and a perforated partition dividing the annular chamber above its lower end and serving to regulate the flow of air to the outlet.

3. The combination with a furnace having 70 a pipe collar, of an annular chamber carried within the said collar and provided with air inlet and outlet openings and a central passage for flue gases; a flue pipe connected 75 with the chamber; a damper for controlling the passage of the products of combustion through the central passage, the damper being pivotally mounted so that a gas explosion will blow it to the open position; and means for releasably locking the damper 80 in an open position, the said means being adapted to permit a gas explosion to blow the damper wide open and to retain it in the position to which it is blown until manually reset.

4. The combination with a furnace, of means associated with the smoke collar of the furnace for supplying fresh air to the interior of the furnace and having a passage for flue gases and a damper for controlling 90 the passage of the flue gases through the passage, the damper being pivotally mounted so that a gas explosion will blow it to the open position; and means for releasably locking the damper in an open position, the 95 said means being adapted to permit a gas explosion to blow the damper wide open and to retain it in the position to which it is blown until manually reset.

Signed at Toronto, Can., this 25th day of 100 July, 1925.

HERBERT C. PAWSON.
